UNITED STATES PATENT OFFICE.

ERNEST LUNN, OF CHICAGO, ILLINOIS, ASSIGNOR TO PULLMAN CAR AND MANUFACTURING CORPORATION, OF CHICAGO, ILLINOIS, A CORPORATION OF ILLINOIS.

BELT-CLEANING DEVICE.

Application filed July 30, 1925. Serial No. 46,954.

This invention relates to belt cleaning devices and more particularly to the rotating type of belt cleaners.

One of the objects of the invention is the provision of new and improved means for removing foreign matter such as snow, ice and the like from transmission belts.

Another object of the invention is the provision of new and improved means for mounting the belt cleaner in such a manner that the same will be held in a fixed relation in proximity to the belt in all positions that the belt may assume.

A further object of the invention is the provision of new and improved belt cleaning mechanism that is cheap to manufacture, easily assembled, composed of few parts, that is efficient in operation, simple in construction and that is not likely to become broken or get out of order.

Other and further objects and advantages of the invention will appear from the following description taken in connection with the accompanying drawings, in which

Fig. 1 is a side elevation of a portion of a railway car showing the invention in position thereon;

Fig. 2 is a plan view thereof;

Fig. 3 is a side elevation of a portion of a railway car, showing a modified form of the invention in position thereon; and

Fig. 4 is a plan view thereof.

Generators for electric lights for railway trains are usually mounted beneath the cars and are driven from the car axles by means of a belt and pulley drive. The belt being exposed is likely to accumulate more or less foreign matter thereon during use, especially during the winter time when snow and ice are prevalent. During a snow storm, for instance, the motion of the train will cause eddy currents of air to carry snow beneath the car, some of which will be deposited on the moving belt. The passing of the belt about the pulley will compress the snow and convert the same into ice, which will cause a serious slippage of the belt with a corresponding decrease in the efficiency of the generator. The present invention seeks to remedy these defects by providing means for removing foreign matter from the belt while the same is in motion.

On the drawing the reference character 10 designates a portion of a railway car beneath which is mounted the generator 11 for

furnishing electricity to the car for operating the lights, the fan, and the like. The generator is operated from the car axle by a belt 12 engaging about the pulley 13 on the armature shaft 14 in the usual manner.

Since the car axles move angularly more or less relatively to the body of the car on curves, the tension of the belt 12 will vary unless means be provided for automatically tensioning the belt. As shown, the generator is provided with one or more rigid arms 15 which are pivoted to the underframe of the car 10 as at 16. The pivot 16 falls without the vertical plane of the armature shaft whereby the weight of the generator 70 will maintain the belt sufficiently taut for operating the armature, and will, at the same time, permit relative angular movement of the axle and car.

The device for cleaning the belt comprises 75 a cleaner member which in the present invention is in the form of a circular brush 17, rotatably mounted in proximity to the surface of the belt.

It is desirable that the cleaner be held in close proximity to, but out of contact with, the belt so that when ice, snow and the like begin to pile up on the belt the cleaner will remove the same without coming in contact with the belt and causing undue wear on the 85 same. Suitable means are provided for causing the cleaner to move in unison with the angular movement of the generator about its pivot 16 for maintaining substantially the same relative position of the belt and 90 cleaner.

In the form of the device selected to illustrate one embodiment of the invention, attaching members or journal plates 18 are secured to the frame work 19 of the car, a supporting rod 21 is journaled in the attaching members or journal plates 18 and has rigidly attached thereto supporting means or arms 22 and 23. A shaft 20 is rotatably mounted in the lower ends of the supporting means 100 23 and the brush 17 is rigidly mounted on said shaft. The arms 22 and 23 are bent so that the shaft 20 extends at an angle to the longitudinal axis of the belt, as clearly shown in Fig. 2 of the drawing.

In order to cause the brush 17 to remain in proximity to the belt 12 during the pivotal movement of the generator 11 about its pivot 16 a crank arm 25 is mounted on one end of the shaft 21 and a link 26 pivotally connects 110

the crank arm 25 to a lug 27 rigidly mounted on the generator casing. The parts are so arranged that as the generator 11 moves about its pivot 16 due to the movement of 5 the axle relative to the car frame on curves and the like, the link 26 will cause a corresponding movement of the brush 17.

The lower ends of the arms 22 and 23 may, if desired, be provided with slots in which 10 are slidably mounted journal blocks 28 in which the shaft 20 is journaled. The blocks 28 may be supported by springs 29 the tension of which may be regulated by set screws 31.

15 In the form of the device shown in Figs. 3 and 4 the supporting arms 33 and 34 are rigidly attached to the underframe 19 of the car, and their lower ends are provided with slots 30 in which are mounted journal blocks 20 35 in which a shaft 36 carrying the cleaner member or brush 17 is journaled. The supporting members or arms 33 and 34 are so arranged that the shaft 36 of the cleaner member 17 extends at an angle to the longitudinal axis of the belt. The blocks 35 are supported by springs 37 the tension of which may be adjusted by set screws 38.

In both forms of the device the belt cleaner member 17 is so mounted that when 30 ice, snow or other foreign matter collects on the belt it will remove the same along the longitudinal center line of the belt. It is found by experiment that this is sufficient, especially where the barrel type or crowned 35 pulleys are employed, as shown in the drawing.

It is thought from the foregoing taken in connection with the accompanying drawings that the construction and operation of 40 my device will be apparent to those skilled in the art, and that various changes in size, shape, proportion and details of construction may be made without departing from the spirit and scope of the appended claims.

45 I claim as my invention:

1. In combination, a driven pulley, a belt for driving said pulley, said pulley being mounted on a pivoted arm, a belt cleaner, and means for mounting said cleaner adjacent to the inner surface of said belt and for automatically maintaining the same contiguous to said belt in any position of said arm, the axis of said means being arranged at an angle to the plane of said belt.

50 2. In combination, a driven pulley, a pivoted arm for mounting said pulley, a belt for said pulley, a belt cleaner, means for mounting said cleaner in proximity to said

belt and means independent of said first named means for automatically adjusting 60 said cleaner when said arm is adjusted.

3. In combination, a driven pulley, a pivoted arm for mounting said pulley, a belt for said pulley, a belt cleaner, means for mounting said cleaner in proximity to said belt and means operatively connected to said arm for automatically adjusting said cleaner when said arm is adjusted.

4. A belt cleaner attachment comprising 70 an attaching member, supporting means pivotally connected to said attaching member, a belt cleaner rotatably mounted in said supporting means, and an adjusting link pivotally connected to said supporting means.

5. In combination, a car frame, a generator, a belt for operating said generator from a car axle, means for movably supporting 75 said generator from said frame so that the same may move in the arc of a circle to compensate for the turning of the car axle relative to the frame, a belt cleaner, means for supporting said cleaner in juxtaposition to the inner surface of said belt and means for holding said cleaner in fixed relation to said belt in all positions of said generator.

80 6. A belt cleaner attachment for generators comprising a hanger means adapted to be pivotally connected to a car frame, a positioning link pivotally connected to said hanger means and having its free end adapted to be connected to said generator and a belt-cleaner member rotatably mounted on one end of said hanger means.

85 7. In combination, a car frame, a driven pulley, means pivotally connected to said frame for mounting said pulley beneath said frame, a belt for operating said pulley, a rotating belt cleaner, and means for yieldably mounting said cleaner on said frame at 90 an angle to the plane of said belt, whereby the brush will remain in the same relative position to said belt in all positions of said pulley and will remove foreign matter from said belt.

95 8. In combination, a driven pulley, movable means for mounting said pulley, a belt for said pulley, a belt cleaner, means for movably mounting said cleaner adjacent to the inner surface of said belt, and means independent of said last named means for automatically maintaining said cleaner in proximity to said belt in all positions of said first named means.

100 In testimony whereof I affix my signature.

110 ERNEST LUNN
